(57) **CLAIM**

The ornamental design for a case for mobile telephones, as shown and described.

DESCRIPTION

FIG. 1 is a rear perspective view of case for mobile telephones showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a front perspective view thereof.

The broken lines in FIG. 7 of drawings illustrate portions of the case for mobile telephones that form no part of the claimed design.
